RIVET EJECTOR

Claggett Offutt, Los Angeles, Calif.

Application March 3, 1942, Serial No. 433,177

2 Claims. (Cl. 78—46)

My invention relates generally to the art of riveting and more particularly to improved means of inserting rivets in their holes preparatory to the actual riveting operation.

Various devices have heretofore been offered to the trade for the holding of a plurality of rivets and for inserting them into their respective holes, but so far as I am aware, none of these has been completely satisfactory. Most of the prior devices have either been too complicated or have been constructed in such manner that the operator had to learn a new technique of riveting in order to use them.

It is the major object of my invention to provide a rivet ejector which the average riveter can use without unusual or excess movements, which will enable him to increase his production by a considerable amount and which will be so simple that it is economical to produce and use.

It is also an object of my invention to provide a simple and efficient ejecting head which can be attached to and used with both mechanically-fed and air-fed rivet tubes with great facility.

A further object of my invention is to provide an improved type of rivet-ejecting head especially adapted for air-feed operation so that the speed of setting rivets is further increased.

Still another object of my invention is to provide a rivet-feeding tube which holds an unusually large number of rivets and which can be conveniently carried on the body of the riveter without in any way interfering with his various operations.

By the use of rivet holding and ejecting means such as shown herein, loose rivets are kept off the floor and the use of rivets of the correct size is assured.

As the result of thorough testing, it has been demonstrated that the forms of my invention illustrated herein accomplish the objects heretofore stated as well as other objects and advantages which will become apparent from the following description of these forms of my invention, taken with the accompanying drawings, in which

Fig. 1 is a perspective view of one form of my rivet-ejecting head shown installed on a tube in which the rivets are mechanically fed.

Fig. 2 is an enlarged vertical longitudinal section of the head shown in Fig. 1 with a rivet in position to be ejected.

Fig. 3 is an end elevation of the head of Fig. 2.

Fig. 4 is a view similar to Fig. 2, but showing the head after the forward rivet has been ejected and the next rivet has been moved into intermediate position.

Fig. 5 is an end elevation of the head of Fig. 4.

Fig. 6 is an enlarged perspective of the escape-
ment mechanism employed in the head of Figs. 1
to 5.

Fig. 7 is a bottom plan view of the head.

Fig. 8 is a perspective utility view of my im-
proved form of rivet-feeding coil adapted for
compressed air feeds.

Fig. 9 is a side elevational view of a modified
10 form of rivet-ejecting head adapted specifically
for an air-operated feed.

Fig. 10 is a vertical section of the modified
form of head taken on the line 10—10 of Fig. 9.

Fig. 11 is a vertical side-elevational section of
15 said head taken on the line 11—11 of Fig. 10.

Fig. 12 is a vertical longitudinal section of still
another form of my rivet-ejecting head which is
suitable for use with both mechanical and air
feeds,

20 Fig. 13 shows a modification of the form shown
in Fig. 12 illustrating a different style of cam op-
eration, and

Fig. 14 is an end view of the modified form
shown in Fig. 13.

25 Referring now to the drawings and particularly
to Figs. 1 to 7 thereof, the numeral 20 designates
what I now consider to be my preferred form of
rivet-ejecting head suitable for both mechanical
and air feeds. For mechanical feeding of the

30 rivets, the head 20 may be attached to the end
of a rivet-holding tube 21 provided with a plunger
22 actuated by a spring 23. The tube 21 is pref-
erably provided with a hole 24 a short distance
35 from its rear end so that when the spring 23 is
compressed into the space between the hole 24
and the rear end of the tube 21, a pin such as a
rivet may be loosely inserted in the hole 24 to
hold the spring in retracted position, thus allow-
ing the tube 21 to be filled with rivets from its
40 open forward end. The plunger 22 is preferably
cylindrical in form and may be provided with an
extending forward portion 25 of reduced diam-
eter, which engages the head of the adjacent riv-
et and will also serve to indicate when the ejector
45 is empty, as will be pointed out hereinafter.

The housing of the rivet-ejecting head 20 is
preferably formed as a cylinder 26 having a bore
27 whose diameter is just slightly larger than the
diameter of the heads of the rivets which are to
50 pass through it. As a convenient means of at-
taching the head 20 to the rivet-holding tube 21,
the rear end of the cylinder 26 may be inter-
nally threaded as shown at 28. The central por-
tion of the housing is preferably enlarged as at
55 29, to facilitate holding it in the hand, and the

upper portion of this enlargement is milled as indicated and then slotted on its upper face to form ears 30 and 31 which accommodate an operating lever 32, which is pivotally mounted on a pin 33 passing across the slot in the ears. So that the forward end of the lever 32 will be continually urged downwardly towards the cylinder 26, a spring 34 is provided which may be seated in a hole 35 on the upper face of the cylinder 26 and arranged to engage the lower face of the rear portion of the lever 32. It is also desirable to supply a stop to limit the movement of the lever 32, which stop can conveniently be in the form of a pin 36 depending from the lower face of the rearward portion of operating lever 32. When the parts are proportioned as illustrated in the drawings, the lever 32 will be in an approximately horizontal position at the end of its stroke.

The big problem in rivet-ejecting devices has always been that of accurately pointing the rivet so that it can be easily inserted in the hole without having to employ additional means at the point of ejection which hinder the removal of the ejecting head after the rivet has been placed in the hole. This problem has been completely overcome by the escapement means now to be described.

Adjacent the forward end of the cylinder 26, I bore a vertical hole through each of the side walls thereof, the holes being spaced so that the central portions thereof pass through the bore 27. These forward holes are designated in the drawings as 36 and 36a, it being seen that they are directly opposite each other on opposite sides of the bore. Similar holes 37 and 37a are bored a short distance back of holes 36-36a and located in relatively the same position. Vertical rods 38 and 38a are slidably mounted in the holes 36-36a, and rods 39-39a are slidably mounted in holes 37-37a. Each pair of rods is suspended from the forward end of the operating lever 32 with a pivotal connection which is preferably loose enough so that the rods may move in a true vertical path without binding, even though the forward end of the lever 32 moves in an arc. A very convenient way of making the pairs of rods 38 and 39 is to form them of fairly heavy wire merely bent in the shape of a U. The U-shaped rods are then slipped through loose-fitting holes on the forward end of lever 32 and allowed to hang in a vertical position so that they may be moved up and down in their respective holes 36 and 37.

The rods 38-38a are cut away or recessed on their inner faces adjacent their lower ends in that portion thereof which is aligned with the bore 27 when the rods are in their uppermost position as shown in Fig. 4. These recessed portions 40 and 40a can be conveniently made by first raising the rods to their upper position and then introducing a boring tool which is just the size of the bore 27, thus with one operation producing the proper size, shape and position of the enlarged or recessed portions 40 and 40a. The rods 39 and 39a are similarly bored by introducing a drill from the rear end of the head when the rods are in the lowermost position as shown in Fig. 2, thus producing recessed portions 41-41a which are offset from recesses 40-40a as seen best in Fig. 6. It will thus be apparent that when the rivet-ejecting head is in normal inoperative position, i. e., when the lever 32 and its associated parts are in the position shown in Fig. 2, that the rods 38 and 38a provide a barrier in the bore 27 which restrains the rivets from passing there-

through and the cut-away portions 41-41a of rods 39-39a are aligned with the bore and provide no barrier therein. It will also be seen that when the head is in the position shown in Fig. 4 that the rods 39-39a have been raised to carry their recessed portions 41-41a out of the bore 27 to thereby create a barrier therein, while the recessed portions 40-40a of rods 38-38a have been raised to alignment with the bore, thus removing the barrier previously formed by said rods.

In operating the rivet-ejecting head 20 just described, it and the tube 21 are filled with rivets of an appropriate size, and the plunger 22 is released to urge the rivets forwardly. With the head loaded, a rivet 42 shown in Fig. 2 is ready for ejection and is held in this position by the tail of rivet 43 pressing against the head of rivet 42, all of the rivets being held together by reason of the spring 23. Depression of the rear end of lever 32 will raise the rods 38 and 39 as previously explained, thus bringing the recessed portions 40 and 40a in alignment with the bore 27, so that the pressure from the spring 23 transmitted through the line of rivets will forcibly eject the rivet 42 into its desired rivet hole if the head has been properly aligned therewith. However, in this position, i. e., the one shown in Fig. 4, it will be seen that the rear rods 39-39a are in their barrier position so that as the second rivet 43 is forced outwardly, its head engages the rods 39-39a and is restrained from moving any further. When the lever 32 is released, the rods all move downwardly to their rest position which causes the rivet 43 to be released by rods 39-39a and forced forwardly a slight distance until its head engages the rods 38-38a as shown in Fig. 2.

When all of the rivets have been ejected from the head and tube in the manner just described, the forwardly extending pin 25 of plunger 22 will project through both pairs of rods and the piston portion 22 will lock in the recessed portion of rods 39-39a, thus preventing operation of the lever 32 and signifying to the operator that the holder is empty, whereupon the head can be removed from the tube and the device can be refilled. It will be apparent that by placing the rods 38-38a fairly close to rods 39-39a that various lengths of rivets can be used in the same head without any modification thereof, which of course is a distinct advantage in that it cuts down the number of heads required on a given job.

Referring now to that part of my invention illustrated in Fig. 8, it will be seen that I provide a relatively long tube, having a forward portion 45 upon the free end of which is mounted a rivet-ejecting head of suitable design, such for example as the head 20 shown in Figs. 1 to 7, and having a coiled portion 46 adapted to be mounted on the body of the riveter in convenient manner as shown. The other end of the rivet-holding tube is attached to an air-hose through a suitable valve 47 to regulate the air pressure therein. By coiling the rivet-holding tube, it is possible to provide space for a very large number of rivets without producing a bulky or unmanageable device, whereas if the tube were not coiled, it would be impossible to handle more than a very short length thereof. From a practical standpoint it is essential that the coil be in such form as will permit it to be mounted directly on the body as shown in Fig. 8 or fastened to the body or the clothing of the riveter by suitable means not shown. By coiling the tube and mount-

ing it on the body, it becomes possible for a person to operate the rivet-ejector with one hand and a rivet hammer with the other without either hindering the operation of the other.

Referring now to Fig. 9 wherein I show an ejector-head that is practically fully automatic and one which is particularly suitable for rapid work and for use in combination with a coiled rivet-holding tube such as shown in Fig. 8, the numeral 50 indicates a housing having a horizontal bore 51 in the upper portion thereof and of a size sufficient to pass rivets therethrough. The head 50 is adapted to be attached to the end of the rivet-holding tube 52 in alignment with the bore 51 and provided with a suitable valve 53 to control the flow of air therethrough. The housing 50 is provided with a vertical bore 54 terminating just below the horizontal bore 51, in which a piston 55 is slidably mounted. An angular passageway 56 connects the rearward portion of the bore 51 with the lower end of the cylinder 54, thus providing an air inlet for the said cylinder, while a passage 57 leads from the upper end of the cylinder 54 to the atmosphere, thus providing an air vent for the upper end of the cylinder.

The upper wall of the head 50 above the bore 51 which I have indicated by the numeral 58 is pierced by four holes which are drilled down through the bore and through the partition between the bore 51 and the bore 54, these four holes being arranged approximately in the manner of the holes 36 and 37 shown in Fig. 7.

Two pairs of rods 60 and 61 are mounted on the forward or upper end of the piston 55 in alignment with the four holes just described and are of such length that when the piston 55 is in its retracted or rest position, as shown in Fig. 10 the upper free ends of the rods will be approximately flush with the top face 58 of the housing and when the piston is in its uppermost position, the rods will be in the position shown in Fig. 11, i. e., extending up beyond the face 58. The forward rods 60 are provided with recessed portions on their inner faces to make an opening the same size as the bore 51, these recessed portions being indicated by the numerals 62, while rearward rods 61 are provided with similar recessed portions 63 offset from the portions 62. These recessed portions are positioned in the same manner as the recessed portions of the rods 38-39, except that they are reversed, i. e., they are staggered so that when the rods are in their lowermost positions as shown in Fig. 10, the recessed portions 62 are aligned with the bore 51 and when the rods are in their uppermost position, shown in Fig. 11, the recessed portions 63 are aligned with the bore 51 and the rods 60 are creating a barrier in the bore. It will be seen that this is just the reverse of the arrangement shown in Figs. 1 to 6 so that the operation is also reversed. However, either system can be employed in either type of head, i. e., they are strictly interchangeable.

A spring 64 is cradled in the space formed between the rods 60-61 in order to return the cylinder to its lowermost position, and a stop 65 which may be in the form of a shoulder in the cylinder 54 is provided to keep the rods from moving too far upward. Similarly, a stop 66 is provided at the lower end of the bore 54 so that when the piston 55 is in its retracted position, the recessed portions 62 of rods 60 will be aligned with the bore 50.

Referring now to Fig. 9, it will be seen that

the angularly positioned passage 56 is provided with an outlet passage 67, which vents passage 56 to the atmosphere. Consequently, when the head is connected to an air hose and the valve opened, air will pass down through the tube and into the horizontal bore 51, part of it passing out around the rivets and part of it by-passing down through the air inlet 56 and hence to the atmosphere through the vent 67. Under these conditions, the spring 64 retains the piston 55 in its retracted position shown in Fig. 10, with a rivet being held in the bore by the rods 61. However, when the vent 67 is closed as by placing one's finger over it, sufficient air passes through the passage-way 56 into the lower end of the cylinder 54 to raise the piston 55 upward, to the position shown in Fig. 11. This brings the recessed portions 63 of rod 61 into alignment with the bore 51 and releases the rivet 68, permitting it to be blown forwardly until its head engages the rods 60, which in this position provide a barrier to the exit of the rivet. As soon as the finger is removed from air vent 67, the air pressure in the lower end of cylinder 54 falls to atmospheric and allows the spring 64 to move the piston and rods back to their lowermost position, thus aligning the recessed portions 62 of rods 60 with the bore 51 and allowing the rivet 68 to be blown out of the head and into its appropriate hole. As previously mentioned, the rods 60 and 61 may be interchanged so that when the air vent 67 is closed, the rivet will be blown out of the ejector and a new rivet loaded in place behind rod 60 when the air vent is again opened and the spring 64 comes into play.

It will be seen that this form of my invention provides a very rapid way of positioning rivets with a very simple mechanism, in which there is only one moving part. Furthermore, the effort expended by the riveter is reduced to a minimum, since he has no levers to operate nor valves to control, the whole operation being accomplished by simply placing his finger over a small hole and then removing it.

Referring now to Fig. 12 wherein I have shown another form of my invention which may be operated with either mechanical or air feeds, the numeral 70 indicates a tubular head having a central bore 71 through which rivets may pass in the manner previously explained. In this form of my invention, instead of utilizing slideable rods to provide the escapement mechanism, I employ two sets of movable members such for example as ball bearings, one set in back of the other, and each independently movable radially of the bore 71. Each set preferably employs a plurality of ball bearings, two being shown in Fig. 12. The forward set comprises ball bearings 72 and 72a, each mounted in sockets 73 and 73a which extend through the walls of the tubular head 70 and are provided with abutments to keep the walls from passing too far into the bore 71. The second set of ball bearings comprising balls 74 and 74a are seated in sockets 75 and 75a in a manner similar to the first set of ball bearings. The ball bearings are of such size that they can be easily forced outwardly or radially by pressure of the rivet head, so as to permit the rivets to pass through the bore 71 unless the balls are restrained in their innermost position.

To restrain the ball bearings alternately, I provide a longitudinally slideable cam 76 which is preferably cylindrical in shape and surrounds the tubular head 70 as indicated. The forward end 75 of the inner face of the cam 76 is provided with

an angular camming face 77, and a similar camming face 78 is provided adjacent the rear end of the cam on its inner surface. The camming faces 77 and 78 are proportioned so that when the cam 76 is in its forwardmost position the balls 72 and 72a will be forced inwardly to create a barrier in the bore 71 and the balls 74—74a will be freely movable in their sockets 75—75a so that they can be moved outwardly by a rivet head pressing on them.

With the head in the position shown in Fig. 12, the cam 76 is moved rearwardly against the force of a spring 79, which abuts against a wall 80 on the rear end of the head 70, thus releasing the pressure on the balls 72—72a and allowing the rivet 81 to be ejected by reason of the force exerted on its head through the rivet 82. However, movement of the cam 76 rearwardly brings the camming face 78 into engagement with the balls 74—74a forcing them inwardly so that they provide a barrier to the movement of the rivet head 82, thus causing it to be restrained at that point. The cam collar 76 is then moved forwardly, permitting the rivet 82 to force the balls 74—74a outwardly and move forward until it is engaged by the balls 72—72a which have again been forced inwardly. It will be seen that by the repetition of this cycle all of the rivets from a tube connected to the rear end of the head may be ejected consecutively as needed.

Since it is advantageous to have the rivets ejected by a forward hand movement, I also provide such a type of cam operation for the ball-bearing form of my invention. This is illustrated in Figs. 13 and 14, wherein it will be seen that the numeral 90 designates a cylindrical housing having a bore 91 for the rivets to pass through. A forward set of radial sockets 92, in this case three, is provided adjacent the forward end of the bore 91, in which movable members such as balls 94 are loosely seated and adapted to restrain the first rivet 99 in the bore when they are held in their innermost position. A similar set of sockets 93 is formed to the rear of the first set and provided with balls 95 likewise adapted to be moved into and out of the bore 91 to alternately restrain and release rivet 100.

In this form of my invention I provide a cylindrical collar cam 96, having forward and rearward internal camming faces 97 and 98 respectively, adapted to engage the forward and rearward sets of balls, respectively. A stop pin 102 may be screwed into the outer face of the housing 90 if desired, access thereto being had through a hole 101 in the cam 96. It will be evident that when the cam 96 is moved forwardly the forward set of balls 94 will be released and forced outwardly by the pressure exerted by the head of rivet 99, while the balls 95 will be held in rivet-restraining position by cam face 98, thus

preventing rivet 100 from following rivet 99 out of the bore. After the rivet 99 has been ejected, the cam is moved rearwardly to release balls 95 and lock balls 94 in restraining position, so that rivet 100 can move forward to a position ready for ejection, i. e., the position formerly held by rivet 99.

It is thus seen that I have provided several forms of my invention, all capable of attaining the objects and providing the advantages previously stated, but it is to be understood that these forms shown in detail herein are merely illustrative of my invention as defined by the appended claims.

15 I claim:

1. A rivet ejector adapted to be connected to a source of compressed air, which includes: a housing having a bore for the passage of rivets therethrough; a cylinder whose axis is substantially normal to that of said bore; a fluid passageway connecting the rear end of said cylinder to said source of compressed air, said passageway having a closable vent to the atmosphere; a piston slidable in said cylinder and adapted to be moved forwardly when said vent is closed; a pair or parallel rods on the forward end of said piston extending through the side walls of said bore and spaced so as to restrain the forward movement of the first rivet therein, said rods having opposed recessed portions on their inner faces spaced to pass the head of said rivet and adapted to be aligned with said bore when said piston is in one position; and means for moving said piston rearwardly when the pressure on its rear end is released, to move the rivet-engaging portions of said rod into said bore.

2. A rivet ejector, which includes: a housing having a rivet-holding bore adapted to be connected to a source of compressed air; a cylinder adjacent said bore having its axis substantially normal to that of said bore and adjacent its forward end; a piston slidable in said cylinder; two pairs of parallel rods on the forward end of said piston, and extending laterally through said bore to restrain the first and second rivets therein respectively, each pair of rods having opposed recessed portions on their inner faces spaced to pass a rivet head, said recessed portions being located so that they are alternately aligned with said bore when said piston is reciprocated, whereby said rivets are alternately restrained and released; a fluid passage connecting the rear end of said cylinder with said air supply; valve means to cause air under pressure to flow into the rear end of cylinder to move said piston forwardly; and a spring housed between said parallel rods adapted to return said piston to its rest position when the pressure behind said piston is released.
